(57) **CLAIM**

The ornamental design for a charge case for electronic device substantially as shown and described.

DESCRIPTION

FIG. 1 is top view of a charge case for electronic device; FIG. 2 is a left side view of the charge case for electronic device;

FIG. 3 is a front view of the charge case for electronic device;

FIG. 4 is a right side view of the charge case for electronic device;

FIG. 5 is a bottom view of the charge case for electronic device;

FIG. 6 is a top view of the charge case for electronic device with a lid open;

FIG. 7 is a left side view of the charge case for electronic device with the lid open;

FIG. 8 is a front view of the charge case for electronic device with the lid open;

FIG. 9 is a right side view of the charge case for electronic device with the lid open; and,

FIG. 10 is a bottom view of the charge case for electronic device with the lid open.

The broken lines which define the bounds of the claimed design form no part thereof.
